UNITED STATES PATENT OFFICE.

CARRIE I. JACKSON, OF PEPIN, WISCONSIN.

WIRE-KNOT.

1,259,869.

Specification of Letters Patent. Patented Mar. 19, 1918.

Application filed August 29, 1917. Serial No. 188,799.

To all whom it may concern:

Be it known that I, CARRIE I. JACKSON, a citizen of the United States, residing at Pepin, in the county of Pepin and State of Wisconsin, have invented certain new and useful Improvements in Wire-Knots, of which the following is a specification.

This invention has relation to a method of forming knots in interlocking strands of wire fencing and has for an object to provide a method of forming a knot which is secure against all strain which may be applied thereto under normal conditions, but which may be united by means of a tool.

In addition to the foregoing my invention comprehends improvements in the details of construction and arrangement of the parts to be hereinafter more fully described and particularly set forth in the appended claim.

In the accompanying drawings in which similar and corresponding parts are designated by the same characters of reference throughout the several views in which they appear:

Figure 1, is a view showing one horizontal and two vertical strands of a wire fencing interlocked in accordance with my invention.

Fig. 2, is a view of one of the knots in side elevation, and

Fig. 3, is a view showing the loops of the notch distorted so as to more clearly illustrate their construction and relation.

With reference to the drawings, 10 indicates the horizontal strand, and 11 the vertical strand of a wire fencing. With particular reference to Fig. 3 it will be seen that the horizontal strand is bent around the vertical strand to form a loop 12 in one direction, and then bent again around the vertical strand in an opposite direction to form a loop 13, whereby the openings in the loops will be in exact vertical alinement. The horizontal strand is then continued on in alinement with the portion of the strand before forming the knot to the next vertical strand where a similar arrangement of loops is formed.

As stated above the loops 12 and 13 thus formed around the vertical strand are arranged with their openings in exact vertical alinement whereby the vertical strand may be passed through both of said loops. To secure the vertical strand in place, that portion thereof between the loops 12 and 13 is grasped by means of a tool, such as a pair of pliers, and a loop formed therein by twisting the tool, said loop being indicated at 14.

Thus it will be seen that the vertical and horizontal strands will be securely locked together absolutely preventing relative movement of the same in any direction. To further secure the strands together, the loops 12 and 13 of the horizontal strand may be pressed together upon the loop 14 by means of pliers to secure the formation shown in Fig. 1.

It will be obvious, that the knot may be readily united or the vertical and horizontal strands disengaged by merely untwisting the loop 14 whereby the vertical strand will be sufficiently straightened to permit its withdrawal from the loops of the horizontal strand.

Having thus described my invention what I claim as new and desire to secure by Letters Patent is:—

The herein described method of forming a wire knot from a horizontal and a vertical strand, which consists in wrapping the horizontal strand around the vertical to form a loop in one direction, then twisting the strand in an opposite direction to form a second loop above the first, then twisting that portion of the vertical strand which is disposed between the loops into a third loop, and finally bending the loops of the horizontal strand toward each other to engage the loop of the vertical strand therebetween.

In testimony whereof I affix my signature in presence of two witnesses.

Mrs. CARRIE I. JACKSON.
